PERPETUAL CALENDAR

Alfred B. Downs, Jr., Columbus, Miss.

Application June 14, 1951, Serial No. 15,541

Term of patent 14 years

(Cl. D74—5)

To all whom it may concern:

Be it known that I, Alfred B. Downs, Jr., a citizen of the United States, residing at Columbus, in the county of Lowndes and State of Mississippi, have invented a new, original, and ornamental Design for a Perpetual Calendar, of which the following is a specification, reference being had to the accompanying drawing forming a part thereof.

Figure 1 is a front elevational view of the perpetual calendar, showing my new design;

Fig. 2 is an end elevational view of the perpetual calendar, of my new design;

Fig. 3 is a perspective view of the perpetual calendar, looking from the rear;

Fig. 4 is a top plan view of the perpetual calendar; and

Fig. 5 is a vertical sectional view taken on line 5—5 of Fig. 1.

The numerals and printed matter shown in

Fig. 1 are merely representative of that which may be expected to appear thereon from time to time.

I claim:

The ornamental design for a perpetual calendar, as shown and described.

ALFRED B. DOWNS, JR.
